UNITED STATES PATENT OFFICE.

FRANK W. MARSTON, OF BOSTON, MASSACHUSETTS.

DRAFT AND BUFFING APPARATUS FOR RAILWAY-CARS.

SPECIFICATION forming part of Letters Patent No. 252,115, dated January 10, 1882.

Application filed August 4, 1880. (Model.)

To all whom it may concern:

Be it known that I, FRANK W. MARSTON, of Boston, Massachusetts, have invented certain Improvements in Means of Transmitting 5 Strains of Traction and Buffing to the Frames of Railway-Cars; and I hereby declare that the following specification is a full, clear, and exact description of the same, and the accompanying drawings are an illustration thereof.

10 My improvement relates to apparatus by which tractional and buffing strains in railway cars and trains are exerted upon springs and continuous metallic connections thereof rather than through such springs directly upon the car-frame.

15 In place of the independent resistance-pieces now commonly in use on the frames of railway-cars, bolted to the draft-timbers and acting as abutments for the draft and buffing apparatus at each end of the car, I substitute two continuous resistance-pieces, which extend from end to end of the car and are firmly bolted or otherwise rigidly secured to the draft-timbers. These continuous resistance-pieces 20 may be made each of a single bar of metal, as shown in Figures 1, 2, 3, and 5; or they may be constructed in two or three sections rigidly connected by intermediate rods, as shown in Figs. 6 and 8. In either case strains of traction applied through the draft apparatus are transmitted through them from end to end of the car; and buffing strains are resisted not by the timbers and bolts alone, in the usual 25 way, but the resistance-plates are bent around 30 and engage with the ends of the draft-timbers 35 of the car-frame, which they materially reinforce.

40 My improvements are embodied in a car-frame provided with two draw-heads, each furnished with a traction and buffing spring held in position by follower-plates, in combination with metallic bars extending from end to end of the car, rigidly fastened to the draft-timbers, and forming continuous cheek-pieces 45 or resistance-pieces for the spring follower-plates to bear upon.

45 My invention also consists in the devices and combination of devices set forth in the appended claims.

50 The drawings illustrate my invention and represent the best form in which I have con-

templated applying it to utilize to the utmost the existing structures.

Figs. 1, 2, and 3 show in plan my improvements and the parts of the bottom frame of 55 a car to which they are applied, Fig. 1 representing the normal condition of the springs, Fig. 2 the springs partially compressed under strains of traction, and Fig. 3 the same wholly compressed, as in buffing. Fig. 4 is a 60 central section of Fig. 1; Figs. 5 and 6, modifications in the form of the connecting-bars, and Figs. 7 and 8 enlarged perspective views of the same.

In the several figures, A A are the central 65 sills of the car-frame, carrying the bolsters B and needle-beams C. D D are draft-timbers, bolted at each end to the under side of the sills A, of which they become practically a part. Their ends abut against the bolsters B. 70

With my improvements I secure to the draft-timbers D, by bolts or otherwise, continuous flat metallic bars E, running from end to end of the car, and bent at right angles, as at E', to cover the ends of the draft-timbers D 75 D. Said bars are also provided near each end with flanged plates or shoulders e e, upon which the spring-plates G bear, and are adapted to receive the strains exerted upon the springs in the movement of the car and 80 transmit them to the draft-timbers, sills, and bolsters of the frame. They serve, therefore, as continuous or longitudinally-connected cheek-pieces or resistance-plates, receiving and transmitting strains in the horizontal plane of the 85 draw-heads, thus relieving the timbers almost wholly.

Draft and buffing strains are exerted primarily upon the draw-heads F, then through the shoulders and keys of the draw-heads upon 90 the spring-plates G G and springs H, confined between them, and next upon the flanges or shoulders e e of the resistance-pieces firmly secured to or formed integral with the bars E E. These bars may continue straight through in 95 the line of the sides of the draft-timbers D D, as in Figs. 5 and 7, and be secured repeatedly to additional draft-timbers J J, bolted to the under side of the sills A between the bolsters; or they may be made in two or three sections, 100 with a connecting-bar, L, as shown in Figs. 6 and 8; but I prefer to bend the bars E in-

wardly and join them along their central parts, as shown in Figs. 1 to 4, that they may reinforce each other, and that the needle-beams C shall be cut into in but a single place. The 5 king-bolts K are between the bars E with either construction.

The action of the parts under the various strains to which they are subjected will be obvious from the drawings. The bars E E', extending across the ends of the draft-timbers, carry the strains into them independent of the bolts and serve as additional means of attachment to the frame. They have no longitudinal or other movement independent of the 15 draft-timbers in any event.

The draft mechanism at each end is independent of the other end, and it exerts all strains upon the metallic bars E E' e, through which such strains as are due to the inertia of each car 20 and its load are distributed to all parts of the car-frame, while train-strains, or strains due to the traction of one or more following cars, are borne by the draft apparatus and the continuous resistance-pieces E e without passing 25 into the sills or draft-timbers. In the case of the rear car of a train, strains of traction or buffing would affect only the spring at the attaching end, that at the other end remaining dormant, having no load to pull or push; but 30 tractional strains at the attaching end would be applied by the bars E E' throughout the length of the car-frame.

I claim as of my invention—

1. A car-frame provided with draw-heads, springs, and follower-plates, in combination 35 with two continuous metallic resistance-pieces for said follower-plates to bear upon, said resistance-pieces being secured to the inner face of the draft-timbers, substantially as set forth.

2. A car-frame provided with independent 40 draft and buffing apparatus at each end, in combination with metallic resistance-pieces rigidly connected or extending continuously from end to end of the sills, and applied directly to the sides and ends of the draft-timbers, substantially as set forth, and for the purposes stated. 45

3. The continuous or rigidly-connected metallic resistance-pieces E E' e, located in the horizontal plane of the draw-heads and secured to the sides and ends of the draft-timbers, so as to transmit to them the tractional strains incident to the movement of a single car, while the traction of the train is borne by said continuous resistance pieces and the draft apparatus which they connect, substantially 50 as and for the purpose set forth. 55

FRANK W. MARSTON.
